RADIATION ABSORPTION CELL FOR OPTICAL TESTING OF FLUIDS

William I. Mann, 1776 Brae Burn Road, Altadena, Calif.

Filed Sept. 5, 1957, Ser. No. 47,614

Term of patent 14 years

(Cl. D16—1)

FIGURE 1 is a perspective view of a radiation absorption cell for optical testing of fluids showing my design;

FIGURE 2 is a side elevational view thereof;

FIGURE 3 is an elevational view taken from the right of FIGURE 2.

FIGURE 4 is a top plan view thereof.

I claim:

The ornamental design for a radiation absorption cell for optical testing of fluids, substantially as shown.
